Primary Examiner — T Chase Nelson

Assistant Examiner — Kelly L Gross

(57) **CLAIM**

The ornamental design for a biochemistry analyzer as shown and described.

DESCRIPTION

1. Biochemistry analyzer

1.1 : Perspective

1.2 : Left

1.3 : Right

1.4 : Back

1.5 : Front

1.6 : Top

1.7 : Bottom

The design relates to a medical biochemistry analyzer; the medical biochemistry analyzer is a diagnostic medical device used for in vitro diagnostics, capable of measuring biochemical diagnostic factors such as cholesterol levels and liver function index using bodily fluids such as blood, saliva, and urine; the material of the design can be synthetic resin or metal.
